United States Patent Office

Des. 186,422
Patented Oct. 20, 1959

186,422

COMBINATION FAUCET HANDLE AND ESCUtCHEON OR SIMILAR ARTICLE

Herbert V. Kohler, Kohler, Wis., assignor to Kohler Co.,
Kohler, Wis., a corporation of Wisconsin

Application January 9, 1959, Serial No. 54,108

Term of patent 14 years

(Cl. D91—3)

Fig. 1

Fig. 2

Fig. 3

Fig. 4

Fig. 5

Fig. 1 is a perspective view of a combination faucet handle and escutcheon showing my new design;

Fig. 2 is a side elevational view of the same;

Fig. 3 is a front elevational view of the combination unit; and

Figs. 4 and 5 are, respectively, top and bottom plan views of the combination faucet handle and escutcheon.

The dominant features of the design reside in the portions shown in full lines.

I claim:

The ornamental design for a combination faucet handle and escutcheon or similar article, as shown and described
